UNITED STATES PATENT OFFICE

LUCIEN L. HAAS, OF BUFFALO, NEW YORK, ASSIGNOR TO BUFFALO PRESSED STEEL CO.,
OF BUFFALO, NEW YORK

MUFFLER

Application filed January 16, 1929. Serial No. 332,948.

This invention relates to mufflers or silencers for use in connection with elimination of noise caused by the flow of gases, for example, from the exhaust manifold from internal combustion engines.

The objects of this invention are to produce a muffler of this kind having a series of nested shells forming a novel arrangement of chambers into which the exhaust gases flow for the purpose of reducing the pressure and eliminating noise caused thereby; also to provide a muffler of this kind with a novel arrangement of passages for conducting gas from one chamber to several other chambers to improve the muffling effect of the device; also to improve the construction of mufflers of this kind in other respects hereinafter specified.

In the accompanying drawings:—

Fig. 1 is a longitudinal central sectional elevation of approximately half of a muffler, a portion of one of the interior shells being completely shown.

Fig. 2 is a central longitudinal sectional view of the other half of the muffler.

Figs. 3 and 4 are transverse sectional views thereof on lines 3—3 and 4—4 of Figs. 1 and 2 respectively.

Figs. 5 and 6 are central sectional elevations similar to Figs. 1 and 2, showing a muffler of slightly modified construction.

Fig. 7 is a transverse sectional view thereof on line 7—7 of Fig. 6.

The muffler includes an outer shell 10, the opposite ends of which are partly closed by means of heads 11 and 12.

The muffler is also provided with an inner shell 14 which in the particular construction shown in Figs. 1—4 extends through the muffler from end to end and is secured at its opposite ends to the heads 11 and 12. For this purpose, these heads may be provided with annular shoulders or offset portions 15 and 16 which receive the ends of the inner shell 14 and if desired, the heads may also

be provided with tubular extensions 17 and 18, the extension 17 communicating with the exhaust pipe of the engine to receive products of combustion discharged from the engine, and the extension 18 forming the discharge of the muffler.

The inner shell 14 is divided by a transverse wall or partition 19 into an inlet and a discharge chamber or portion.

The annular space formed between the outer and inner shells 10 and 14 is preferably divided into two compartments by means of a transverse partition 20. This transverse partition in the particular construction shown is provided with inner and outer cylindrical flanges which are secured to the inner and outer shells of the muffler in the usual manner.

Either or both of the two compartments at opposite sides of this partition may be divided into a plurality of flow passages or muffling chambers. In the particular construction illustrated, only one of these compartments is so divided, namely, the one adjacent to the intake of the muffler, this compartment being divided into two spaces by a substantially frusto-conical shell 22, one end of which in the construction shown also engages the shouldered portion 14 of the head 11 and the other end of which is secured to a shoulder 23 of the transverse partition 20. This frusto-conical shell 22 is preferably so formed that the larger end thereof is elongated or substantially elliptical in cross section, while the other or smaller end thereof is of circular cross section. This formation of the shell 22 is effected by forming the shoulder 23 on the transverse partition 20 of elliptical shape as is clearly shown in Fig. 4, and then fitting the larger end of this shell over the shoulder and securing the same thereto.

As a result of this construction the two chambers into which the compartment is divided by the wall 22 are of irregular shape having some portions of greater cross sec-

tional area than other portions, so that a very effective muffling is produced by causing the gases to flow in these chambers through the spaces of varying cross sectional areas.

5 Other forms of shells or partitions may be provided in the muffler, if desired.

The inlet portion of the inner shell 14 of the muffler is provided with an opening or series of apertures 25 into which the major portions of the gases entering the shell pass. From these apertures the gases pass into that portion of the surrounding chamber which is of reduced cross sectional area as shown in Fig. 4. The gases expand in this chamber 10 by flowing radially toward the portion thereof of larger cross sectional area and longitudinally toward the discharge opening in the intermediate shell 22 which is in the form of a series of apertures 26. These apertures 15 are so arranged with reference to the apertures 25 that the gases in the chamber between the inner shell 14 and the shell 22 must pass through approximately a quarter of a turn to reach the discharge opening 26. The 20 gases after passing through the discharge opening 26 are in the outer chamber and flow lengthwise in this chamber and through apertures 27 formed in the transverse partition or wall 20 into the compartment between 25 the inner shell 14 and the outer shell 10 and adjacent to the discharge end of the muffler. From this compartment the gases pass into the discharge chamber of the inner shell through a series of openings 28 arranged at 30 opposite sides of the inner shell, and the gases are consequently discharged from the muffler 35 through the discharge passage 18.

In order to assist in the muffling of the gases it has been found very effective to discharge 40 some of the gases through an opening or apertures near the intake end of the inner shell 14, and for this purpose openings 29 are provided, these openings being of such size as to permit only a relatively small part 45 of the gases to flow through the same.

However, the gases which flow through the openings 29 pass toward the apertures 26 in the shell 22 in a direction opposite to the direction of travel of the gases which have been 50 passed through the main discharge openings 25 of the receiving portion of the inner shell, and this flow in opposite directions assists in the muffling of the noise.

A further improvement in the silencing of 55 the noise of the gases, and a simultaneous reduction in the back pressure produced by the muffler results in the providing of additional openings or apertures 31 in the intake portion 60 of the inner shell and beyond the transverse partition 20. These apertures are also of fewer number or of smaller size than the apertures 25 so that only a small portion of the gases entering the intake part of the inner shell passes through the openings 31. 65 These gases, however, pass directly into the

final expansion compartment of the muffler and therefore do not have to pass through the several chambers of the preliminary expansion chamber and thus to a certain extent 70 reduce the back pressure caused by the muffler. By discharging the gases radially into contact with the longitudinally flowing gases passing out of the apertures 27 in the transverse partition 20, a muffling of the noise results.

The muffler shown in Figs. 5 to 7 is similar in construction to the one shown in Figs. 1 to 4 except that the inner shell of the muffler in this case does not extend throughout the 80 length of the muffler. In this construction the outer shell of the muffler may be made somewhat shorter and the inner shell 34 terminates at a transversely extending partition or head 35 which corresponds substantially to the transverse head 20 shown in Figs. 1 to 4 but which has a central imperforate head 36 around which the inner shell 34 fits and which closes the end of the inner shell.

The intermediate shell 22 is the same as shown in Figs. 1 to 4 and consequently the arrangement of the shells and the chambers formed thereby in the compartment extending from the partition 35 to the head 11 at the receiving end of the muffler are the same as in the other construction. The space between the partition 35 and the head 12 forms a compartment 38 into which the gases enter through the discharge openings 39 in the intermediate head or partition 35, and after expanding in the chamber 38, the gases pass out through the extension 18 of the head 12. This muffler is of somewhat simpler form than the one shown in Figs. 1 to 4, and has been found very satisfactory for use in connection with somewhat smaller engines.

The muffler in both of the forms described is of inexpensive construction and consists of relatively few parts, and it will be noted that the structure results in the gases flowing from the inlet to the discharge of the muffler through chambers which increase successively in size, which has been found to produce an improved muffling effect, and with less back pressure than is commonly produced in mufflers having an equal silencing effect.

I claim:

1. In a muffler, the combination of an outer shell, a transverse partition dividing said shell into two compartments, said partition having passages therethrough through which gases may flow from one compartment to the other, an inner shell extending through said muffler and said partition, a transverse dividing wall in said inner shell and arranged out of alignment with said partition, the portion of said inner shell at one side of said dividing wall receiving gases and the other portion of said inner shell discharging gases from the muffler, said first mentioned portion of said inner shell being provided with aper-

tures communicating with the compartments at both sides of said partition and said other portion of the inner shell being provided with apertures communicating with only one of 5 said compartments, whereby the flow of incoming gases is distributed to both of said compartments.

2. In a muffler, the combination of an outer shell, a transverse partition dividing said shell into two compartments, said partition having passages therethrough through which gases may flow from one compartment to the other, an inner shell extending through said muffler and said partition, a transverse dividing wall in said inner shell and arranged out of alignment with said partition, the portion of said inner shell at one side of said dividing wall receiving gases and the other portion of said inner shell discharging gases 20 from the muffler, the gas receiving portion of said inner shell being provided with openings communicating with both compartments at opposite sides of said partition, and said other portion having apertures communicat- 25 ing with only one of said compartments.

3. In a muffler, the combination of an outer shell, a transverse partition dividing said shell into two compartments, said partition having passages therethrough through which 30 gases may flow from one compartment to the other, an inner shell extending through said muffler and said partition, a transverse dividing wall in said inner shell and arranged out of alignment with said partition, the portion of said inner shell at one side of said 35 dividing wall receiving gases and the other portion of said inner shell discharging gases from the muffler, the gas receiving portion of said inner shell being provided with apertures through which the major portion of 40 the gases pass into the compartment adjacent to the inlet end of said muffler and a restricted opening through which a lesser portion of the incoming gases may pass to the other 45 compartment, the discharge portion of said inner shell being provided with openings through which gases may pass from said last mentioned compartment.

4. In a muffler, the combination of an outer shell, a transverse partition dividing said shell into two compartments and having passages therethrough through which gases may flow, an intermediate shell arranged in one of said compartments for dividing the same 55 into muffling chambers, said intermediate shell having passages through which the gases may flow from one of said chambers to another, an inner shell in said muffler, a transverse wall in said inner shell dividing the 60 same into gas receiving and gas discharging portions, a main discharge opening in said gas receiving portion through which gas may be discharged into said muffling chambers at one side of said transverse partition and a 65 lesser opening through which a relatively

smaller portion of said gases may be discharged into the compartment at the other side of said partition, and apertures in the discharge portion of said inner shell communicating with said last mentioned compartment through which gases may pass from said last mentioned compartment to the discharge portion of said inner shell. 70

5. In a muffler, the combination of inner and outer shells, heads connecting the end portions of said shells, a transverse partition intermediate of said heads and extending from said inner shell to said outer shell and dividing the space between said inner and outer shells into two compartments, a transverse wall in said inner shell dividing the same into gas receiving and gas discharging portions, an intermediate shell arranged in the compartment adjacent to the gas receiving end of the muffler, passages through said inner and intermediate shells and said partition to cause gas from the receiving portion of said inner shell to flow first through chambers formed in one of said compartments by said intermediate shell and then to the other 80 portion of said inner shell, and an opening in said receiving portion of said inner shell for discharging a lesser portion of gas entering the 85 receiving portion of said inner shell directly into said other compartment in a direction at an angle to the flow of gas into said other compartment through said apertures in said transverse partition. 90

6. In a muffler, the combination of an outer shell, heads connected to said outer shell adjacent to the ends thereof, one of said heads being provided with an inlet opening for admitting gases to the muffler and the other 105 head having a discharge opening for the gases, a transverse partition arranged between said inner and outer heads and dividing said muffler into two compartments, an inner shell communicating at one end with the inlet opening in one of said shells, an intermediate shell arranged in the compartment at the inlet end of the muffler and extending from the head at the inlet end thereof to said transverse partition and being of smaller diameter at the portion thereof adjacent to the inlet head than at the portion thereof adjacent to said partition, said inner shell having discharge openings for gases arranged adjacent to said partition, said intermediate shell 110 having discharge openings arranged at a distance from said partition, and said transverse partition having discharge openings adjacent to said outer shell through which gases may pass from the compartment adjacent to the inlet end of the muffler to the other compartment. 115

7. In a muffler, the combination of an outer shell, heads connected to said outer shell adjacent to the ends thereof, one of said heads

- being provided with an inlet opening for admitting gases to the muffler and the other head having a discharge opening for the gases, a transverse partition arranged between said inner and outer heads and dividing said muffler into two compartments, an inner shell communicating at one end with the inlet opening in one of said shells, an intermediate shell arranged in the compartment at the inlet end of the muffler and extending from the head at the inlet end thereof to said transverse partition and being of smaller diameter at the portion thereof adjacent to the inlet head than at the portion thereof adjacent to said partition, said inner shell having a relatively large number of discharge openings adjacent to said transverse partition and a smaller number of discharge openings adjacent to said inlet head and said intermediate shell having discharge openings arranged intermediate of the discharge openings in said inner shell, whereby gases will flow in opposite directions in the space between the inner and intermediate shells, said partition having discharge openings adjacent to the outer edges thereof for permitting gases to flow from the compartment adjacent to the inlet end of the muffler to the other compartment.
8. A muffler having inner and outer substantially cylindrical shells and an intermediate substantially conical shell, heads to which the ends of said shells are secured, said shells and heads forming chambers in which the gases flow and which chambers have converging walls, and apertures in said inner and intermediate shells for causing the gases to flow into the larger ends of said chambers.
9. A muffler having inner and outer substantially cylindrical shells and an intermediate tapering shell, heads to which the ends of said shells are secured, said heads having shouldered portions to which said shells are secured, said tapering shell being secured at one end to the same shouldered portion as one of said other shells, said shells and heads forming converging chambers in which the gases flow, and said inner and intermediate shells having apertures through which gases flow into the larger ends of said chambers.
10. In a muffler, the combination of an inner and an outer substantially cylindrical shell, an intermediate substantially conical shell which is substantially elliptical at one end thereof, and heads to which said shells are secured, said shells having passages for conducting gases successively into the ends of greatest cross sectional area of the several chambers formed by said shells and heads.
11. In a muffler, the combination of an inner and an outer substantially cylindrical shell, an intermediate substantially conical shell which is substantially elliptical at the larger end thereof, heads to which the ends of the shells are secured, said shells and heads

forming chambers with converging walls through which gases flow, said inner and intermediate shells having apertures for discharging gases into larger portions of said chambers, said inner shell having its apertures arranged to discharge the gases adjacent to the minor axis of the elliptical curvature of the larger end of said intermediate shell.

12. In a muffler, the combination of alternately arranged shells of substantially circular and elliptic cross section, at least one of said shells tapering to form chambers between shells varying in cross sectional area from one end of each chamber to the other end thereof, heads to which the ends of the shells are secured to cooperate with said shells to form said chambers, and apertures in the shells to conduct gases into the chambers between adjacent shells into the end of greater cross sectional area of each chamber.

LUCIEN L. HAAS.
